UNITED STATES PATENT OFFICE.

RUDOLPH GNICHWITZ, OF ASHBURNE, ASSIGNOR TO THE MATHER MANUFACTURING COMPANY, OF PHILADELPHIA, PENNSYLVANIA.

DESIGN FOR A FONT OF PRINTING-TYPE.

SPECIFICATION forming part of Design No. 20,364, dated December 2, 1890.

Application filed November 5, 1890. Serial No. 370,426. Term of patent 7 years.

To all whom it may concern:

Be it known that I, RUDOLPH GNICHWITZ, a citizen of the United States, residing at Ashburne, in the county of Montgomery and State 5 of Pennsylvania, have invented a certain new and useful and original Design for a Font of Printing-Type, of which the following is a full, clear, and exact description.

The leading features of this design for a 10 font of printing-type are the heavy swells or shadings at the top and bottom of capitals, the harp-string lines crossing the capitals, the curled terminals of capitals and lower-case, the logotypes "Co." and "No." top and 15 bottom swells or shading in lower-case letters, and the pointed terminals, heavy swells or shading, and curls or scrolls of the numerals, in addition to the general script-like shape or configuration of the various characters 20 forming the font of printing-type.

The font includes capitals, lower-case, numerals, punctuation-marks, and logotypes, the &, \$, and £, all of substantially the shape and configuration shown in the annexed drawing or impression, and all of the several characters include one or more of the leading features of the design above specified. 25

What I claim is—

The design for a font of printing-type, substantially as shown and described. 30

In testimony whereof I have hereunto set my hand this 4th day of November, A. D. 1890.

RUDOLPH GNICHWITZ.
